FUSE FOR BOMBS

Hermann H. Zornig, United States Army,
Newhall, Iowa

Application June 20, 1935, Serial No. 27,531

4 Claims. (Cl. 102—36)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a fuse for bombs.

The purpose of the invention is to provide a delay arming mechanism for a fuse which employs reduced motion gearing.

10 The invention is characterized by a novel arrangement in which a planet pinion carried by a rotor is meshed with a pair of gears which are both longitudinally displaceable with a spindle.

To these and other ends, the invention consists in the construction, arrangement and combination of elements described hereinafter and pointed out in the claims forming a part of this specification.

A practical embodiment of the invention is illustrated in the accompanying drawing, where-

20 in:

Fig. 1 is a longitudinal sectional view partly in elevation of a fuse constructed in accordance with the invention and showing the parts in the safe or unarmed position.

25 Fig. 2 is a similar view with the parts in armed position.

Fig. 3 is a sectional view on the line 3—3 of Fig. 1.

Referring to the drawing by characters of reference, there is shown a fuse casing 5 which is attached to a bomb 6 and which carries a firing mechanism comprising a primer 7 and an inertia plunger 8 whose firing pin 9 is normally held clear of the primer by means of a spring 10. A pin 11 in the casing extends into a longitudinally disposed groove 12 in the plunger and holds the plunger against rotation while permitting it to move longitudinally of the casing.

30 A spindle 13 having its inner end threaded engaging the plunger 8 and a cap 14 on the casing 5, extends through a tube 15 fixed on the cap, and passes through a guide plug 16 in the front end of the tube. The plug 16 also serves to retain a cup 17 in place on the end of the tube.

45 The outer projecting end of the spindle carries a sleeve 18 which is secured by means of a pin 19. The sleeve is formed with a flange 20 which cooperates with the inner end of a nut 21 threaded on the sleeve to establish an inner race for ball bearings 22. A rotor 23 has a groove 24 which establishes the outer race for the ball bearings. A flange 25 on the nut 21 extends across the clearance between rotor and nut to protect against entry of foreign matter. A nut 26 50 on the rotor carries vanes 27 which are acted on

by air pressure during flight of the bomb to produce rotation of the rotor. The rotor is formed with an apron 28 dimensioned to fit within the cup 17 and enclose elements of the fuse.

A nut 29 on the inner end of the sleeve 18 retains a plate 30 which is movable longitudinally with the spindle but is held against rotational movement by a pin 31 which it carries and which is inserted through an aperture 32 in the floor of the cup 17. 5

10 A gear 33 fixed on the plate 30 and having for example twenty-nine teeth is positioned adjacent a gear 34 fixed on the sleeve 18 and having for example thirty teeth. A pinion 35 meshing with the gears 33 and 34 is carried on a shaft 36 which 15 is mounted in the rotor 23.

15 When the fuse is in transportation and storage the plunger 8 and spindle 13 are positively held against movement by their respective cotter pins 37 and 38. These pins are removed when the 20 bomb is placed in the launching rack of an aircraft and an arming wire 39 inserted through apertures in the vane and cup and through a ring 40 secured to the rotor. This arming wire is withdrawn in a well known manner when the bomb 25 is launched.

When the bomb is launched the air pressure acts on the vanes to spin the rotor 23 which moves on the ball bearings. The pinion 35 carried by the rotor is moved as a planet about the 30 gears 33—34. Since the gear 33 with twenty-nine teeth is held against rotation the gear 34 with thirty teeth can only move through the distance of one tooth for a complete revolution of the planetary pinion 35. The rotor must therefore revolve twenty-nine times in order to turn the spindle 13 through a single revolution thereby increasing the arming time twenty-nine times, after which the parts are in the position shown in Fig. 2 with the plunger 8 armed and capable 35 of functioning on impact. 40

I claim:

1. In a fuse, a casing, an element of a firing mechanism in the casing, a cup on one end of the casing, a spindle threaded in said element and 45 passing through the cup, a sleeve fixed on the end of the spindle and having a flange, a nut on the sleeve cooperating with the flange to establish an inner race, a rotor having a groove establishing an outer race, ball bearings between the races, 50 vanes on the rotor, a skirt on the rotor dimensioned to lie within the cup on the casing, a gear fixed on the sleeve and disposed within the skirt of the rotor, a gear non-rotatably carried by the sleeve, said last named gear having less teeth 55

than the fixed gear on the sleeve, and a pinion carried by the rotor and meshing with both of the gears.

2. In a fuse, a casing, an element of a firing mechanism in the casing, a cup on one end of the casing, a spindle threaded in said element and passing through the cup, a sleeve fixed on the end of the spindle and having a flange, a nut on the sleeve cooperating with the flange to establish an inner race, a rotor having a groove establishing an outer race, ball bearings between the races, vanes on the rotor, a skirt on the rotor dimensioned to lie within the cup on the casing, and gearing housed within the skirt of the rotor for moving the spindle on rotation of the rotor.

3. In a fuse, a casing, an element of a firing mechanism in the casing, a spindle threaded in

said element, a sleeve fixed on the spindle, a gear fixed on the sleeve, a rotor mounted on the sleeve, a plate carried by the sleeve, means for holding the plate against rotation, a gear fixed on the plate and having less teeth than the gear on the sleeve, and a pinion carried by the rotor and meshing with both of the gears.

4. In a fuse, a spindle, a member in threaded engagement with the spindle, a rotor rotatable relative to the spindle, a gear fixed on the spindle, a non-rotatably mounted gear movable longitudinally with the spindle, said gear having less teeth than the gear fixed on the spindle, and a pinion carried by the rotor and meshing with both gears.
